FOREIGN PATENT DOCUMENTS

DE 9415962 1/1994

Primary Examiner — T. Chase Nelson

Assistant Examiner — Kathleen M Sims

(57) **CLAIM**

The ornamental design for a wand, as shown and described.

DESCRIPTION

FIG. 1 is an isometric view of a wand according to our new design;

FIG. 2 is a front elevation view of the wand of FIG. 1;

FIG. 3 is a rear elevation view of the wand of FIG. 1;

FIG. 4 is a left side elevation view of the wand of FIG. 1;

FIG. 5 is a right side elevation view of the wand of FIG. 1;

FIG. 6 is a top plan view thereof; and,

FIG. 7 is a bottom plan view of the wand of FIG. 1.

The broken lines represent environmental structure and form no part of the claimed design.
